UNITED STATES PATENT OFFICE.

CHARLES H. WILLCOX, OF NEW YORK, N. Y., ASSIGNOR TO THE WILLCOX & GIBBS SEWING MACHINE COMPANY, OF SAME PLACE.

CONNECTING-ROD.

SPECIFICATION forming part of Letters Patent No. 398,761, dated February 26, 1889.

Application filed November 20, 1888. Serial No. 291,336. (No model.)

To all whom it may concern:

Be it known that I, CHARLES H. WILLCOX, of New York city, in the county and State of New York, have invented a new and useful 5 Improvement in Connection-Rods, which improvement is fully set forth in the following specification.

This invention has reference to the construction of connection-rods for communicating motion from a ball-eccentric to a lever or other vibrating part, and has special, though not exclusive, reference to the construction of the connection-rod for a Willcox & Gibbs sewing-machine, by which motion is communicated to the needle arm or lever.

As heretofore constructed, the connection-rod has had on one face a counterbored recess for the reception of a flange or collar on the band-wheel or pulley adjacent to the ball-eccentric, by which the connection-rod is reciprocated. Inasmuch as the upper end of the connection-rod is pivoted to the needle-lever by a ball-stud the connection-rod necessarily has a slight oscillating motion on the ball-eccentric, this motion being on an axis passing centrally through the eccentric transverse to the shaft. In order to allow this slight oscillating movement, it has been necessary to leave a free space all around the said flange between it and the adjacent face of the counterbored recess in the connection-rod, which construction also permitted the connection-rod to oscillate on an axis passing through the eccentric and ball-stud, and to prevent this undesirable oscillation without interfering with the necessary oscillation on a horizontal axis is the object of the present invention.

Instead of making the face of the counterbored recess a plane surface as heretofore, it has a raised portion or edge approaching and touching or practically touching the adjacent face of the revolving flange. This edge is formed on each side of the recess at about the middle thereof, and from this edge the face of the recess is cut away at an angle, forming a space between it and said flange which gradually increases in width in both directions. Consequently the connection-rod can oscillate slightly upon an axis parallel 50 with this raised edge, but is prevented from oscillating in any other direction.

The invention is not limited in its application to a connection-rod having a counterbored recess for the reception of a running flange, but may be applied to any connection-rod required to oscillate on a ball-eccentric, and having either a rotating or a stationary surface adjacent to it. In such case the face of the connection-rod on each side of the eccentric is provided with a raised portion or edge approaching and touching or almost touching the adjacent surface.

In the accompanying drawings, which form part of this specification, Figure I is an elevation, partly in section, of a portion of a 65 Willcox & Gibbs sewing-machine; Fig. II, a horizontal section of the wheel and connection-rod; Figs. III, IV, and V, detail views of a portion of the connection-rod.

A represents the main shaft; a, the ball-eccentric thereon; B, the wheel; C, the connection-rod; D, the needle-lever, and d the ball-stud connecting the connection-rod with the needle-lever.

The wheel B has a flange, b, which projects 75 into a counterbored recess, c, in the opposing face of the connection-rod. The inner vertical face of recess c, instead of being a plane surface, as heretofore, is inclined away from the flange b both upward and downward from 80 a horizontal line or edge, e, on each side of the eccentric. This edge or line e touches or nearly touches the rotating flange b, and is parallel with the axis on which the connection-rod oscillates; but the contact of the edge 85 e with the flange b on both sides of the recess prevents any vibration or oscillation of the connection-rod on a vertical axis.

In practice the highest portion of the edge e may be a portion of an arc struck from the 90 center of the balled-out recess, as indicated in Fig. V, this point being in the axis upon which the rod C oscillates, and the recess is conveniently formed by means of an end mill of the proper size.

It will of course be understood that the invention is not limited to the precise machine or construction shown, which is illustrated merely by way of example.

Having now fully described my said invention, what I claim, and desire to secure by Letters Patent, is—

1. The combination of a shaft, a ball-eccentric thereon, a connection-rod mounted on said eccentric and adapted to convey motion to a vibratory part, and a part—such as a flange—having a surface adjacent to said connection-rod, the latter being provided with a raised portion or edge on each side of the eccentric touching or nearly touching said adjacent part, and being cut away from the surface of said part on both sides of said raised portion or edge, so that said rod can oscillate on said eccentric on an axis parallel with said edge, but is prevented from oscillating in any other direction, substantially as described.
- 15 2. The combination of the shaft, ball-eccentric, vibrating lever, connection-rod for communicating motion from said eccentric to said lever and provided with an annular counter-

bored recess on one face, and a wheel on said shaft having a flange extending into said recess, the face of said recess adjacent to said flange being formed with a raised portion or edge touching or nearly touching said flange, and being cut away from the latter at an angle, so that the connection-rod can oscillate on an axis parallel to said raised portion or edge, but is prevented from oscillating on an axis perpendicular thereto, substantially as described.

In testimony whereof I have signed this 30 specification in the presence of two subscribing witnesses.

CHAS. H. WILLCOX.
